Jonathan Russell of Granville New York.
Letters, Letters

The subscriber refers to my last letter to him and making part of the same containing a description in the words of the said Jonathan A. Russell himself of his improvement in the machinery for packing Specie and Flour.

It is known that Jonathan A. Russell of Granville Washington County State of New York have made some and useful improvements being a machine for packing flour into barrels for market, by a screw's weight which is described as follows: reference being had to the annexed drawings of the same making part of this description.

In this machine the offensive laborious & unwholesome method of collecting, punching and levelling flour into barrels is rendered unnecessary. The principal feature of my machine consists in the pressing the flour by means of a screw about the edge of a barrel head commencing at the bottom of the barrel and rising according to the shape of the machinery to the top. The machine consists of a suitable frame (a) to contain the machinery, in the centre of which frame is a vertical shaft (b) having a drum (c) on its lower end about the edge of a barrel head for the purpose of finishing the flour. On this shaft is a drum (d) about 4 or 3 feet long and of any required diameter turned by a band from the driving power which drum is weighed for the purpose of giving the necessary pressure to the flour. Near the upper end of the shaft is a male screw (e) working in a female screw (f), made in two parts connected together by a joint (g) in such a manner that they may be opened when it is required to throw the screw out of gear, and closed when required to be thrown in gear in order to save the screw power entirely from the barrel. The opening and closing of the female screw is effected by a piece of iron (h) shaped something like a N connected to and operated by a lever (i) turning on a pin the lever being moved by a rod (k). The upper end of the shaft (l) is shaped like a screw, to which is attached loosely a ball (m). To this ball is connected a trigger (n) passing through

a nail (p) placed on the top of a coarse piece of the frame for the purpose of lowering gradually the screw presser to the bottom of the Barrel, there being projections (q) on the Ball, striking against corresponding projections (r) on the screw head which thus connects the shaft and screw together and cause them to turn in the same direction in descending.

An inclined shaft (s) to receive the flour from the elevators, and convey it to the barrel is inserted in the frame in a suitable and convenient manner. The operation of the machine is, as follows.

An empty barrel is placed under the screw presser its centre being in a line with the centre of the shaft. The female screw is opened by the lever and apparatus for that purpose, the screw presser is then lowered to the bottom of the barrel. The driving machinery being set in motion by water or other power, the band from it, passing round the drum, turns it and the shaft on which it is fastened, and also the screw presser at the lower end of the shaft, the flour all the time running in to the barrel from the press, having been raised from the meal chest by common elevators and passed through the screw press, the shaft passing of which gathering it in whilst the screw being pressed it evenly and equally from the bottom to the top of the barrel to any degree of compactness, according the weight put on the shaft of the presser.

When the barrel is full the female clamp screw is closed which holds the mill stone in gear and raises the screw presser entirely out of the barrel and holds it in a stationary position. This barrel is then removed, and an empty barrel put in its place, and the operation repeated as before described. One person only is required to take away the full barrel and replace it with another, ^{the time} without loss of time. Without these minutes is all that is required to press a barrel of flour. Though the manual labour is, not more than four seconds and during the operational bursts no hoop is and no flour is pressed out at the sides of the barrel as it passes, the flour even and equally throughout. One man with this machine can press as many barrels of flour in any given time as he can weigh and head up. He may pack weigh and nail off about 60 barrels per hour with a machine which I have made and used with

a view to test the improvement. The size and proportion of the machine may be varied and its motion graduated so as to work faster or slower.

What I claim as my improvement, and which has never before been known is the before described machine for pressing flour into barrels, particularly the mode of pressing it by a screw on the end of a weighted shaft and working upward from the bottom of the barrel as herein set forth. However I do not intend to confine myself to the exact form and dimensions which I have described in the foregoing specification and drawings, but I intend to vary the same to suit circumstances, whilst similar results are attained by means substantially the same.
